GLOVE

Edward Elkus, San Francisco, Calif., assignor to
 The Boss Manufacturing Company, Kewanee,
 Ill., a corporation of Illinois

Application June 1, 1934, Serial No. 728,596

1 Claim. (Cl. 2—161)

This invention relates to improvements in gloves, and more especially to the class of gloves which have leather facings or palm portions and are known as workmen's gloves.

5 Objects of the invention are to provide an improved glove of the type referred to, to provide an improved workmen's glove having a leather palm and a cloth back in combination with a full leather thumb, the construction being so designed that all
 10 portions of the glove subject to the greatest wear are of leather and a strong, durable, and inexpensive construction is afforded.

The invention with other objects and advantages thereof and the particular form, combination, and arrangement of parts comprising the same will be understood from the following detailed description when considered in connection with the accompanying drawings forming part hereof and illustrating two embodiments of the
 20 invention.

In the drawings,

Figure 1 is a plan view of the front of a glove constructed in accordance with the present invention;

25 Figure 2 is a similar view of the back of the glove;

Figure 3 is a section on the line 3—3 of Figure 1;

Figure 4 is a plan view of the pattern or blank for the front of the glove;

30 Figure 5 is a view of the blank for the back of the thumb;

Figure 6 shows the blanks for the back of the glove;

Figure 7 is a view of the blank for one of the
 35 leather facings for the backs of the tip portions of the fingers;

Figure 8 is a view of the reinforcing strip interposed in the seam extending along the crotch between the thumb and forefinger;

40 Figure 9 is a plan view of the palm side of a modified construction;

Figure 10 is a fragmentary plan of the back of the glove illustrated in Figure 9;

Figure 11 is a view of the pattern for the palm
 45 of the glove shown in Figure 9;

Figure 12 shows the blank for forming the front portion of the second and third fingers; and

Figure 13 is a view of the blank for the back of the glove.

50 While specific embodiments of the invention are illustrated in the drawings, it will of course be understood that minor changes may be made in the particular constructions shown and the invention may be embodied in other forms as will appeal to those skilled in the art and falling with-

in the scope of the appended claim without departing from the spirit of the invention.

Referring to a detailed description of the particular embodiment of the invention illustrated in Figures 1 to 8 of the drawings, the construction shown comprises the blank 1, illustrated in Figure 4, formed from a continuous piece of leather and including a palm section 2, portions 3, 4, 5, and 6 adapted to form the fronts of the fingers, and a part 7 projecting from one side of the blank and designed to form the front of the thumb. In providing said thumb piece, the blank is cut to form a straight slit 8 extending downwardly and inwardly from one side edge thereof; and, as shown, the blank has a curved edge portion 9 extending upwardly from its lower edge to the adjacent curved edge of the thumb piece. A blank 10 is provided to form the back of the thumb, the same comprising a main part 10' to match the thumb part 7 of the blank 1 and having at one side of said main part the straight edge portions 11 and 12 to match the straight edge portions bordering the slit 8 in the blank 1. The straight edge portions 11 and 12, as shown, diverge downwardly substantially away from each other and converge to a substantially projected intermediate portion. The back thumb piece 10, like the blank 1, is made of leather.

The back of the glove is formed from a plurality of blanks or strips 13, 14, 15, and 16 of cloth laid parallel and the marginal portions of adjacent strips being united by stitching, said strips constituting the main back portion of the glove and also the backs of the fingers.

In forming the glove, the front thumb piece 7 is folded back and the main part 10' of the thumb piece 10 is stitched thereto and to the adjacent curved edge portion 9 of the palm section 2. The straight edge portions 11 and 12 of the thumb piece 10 are stitched to the straight marginal edge portions that extend along the slit 8, and the adjoining side edge of the thumb back piece is secured to a side edge portion of the back of the glove. The cloth back is then secured to the front of the glove by stitching at the side edges and by stitching the edges of the finger portions of the front of the glove to the edges of the finger portions of the back of the glove. 17 designates a reinforcing strip interposed in the seam extending along the crotch between the thumb and finger, and 18 and 19 are linings of any suitable material for the palm portion, the leather fronts of the fingers, and the thumb. Leather facings 20 are provided for the backs and sides of the tip portions of the fingers, said facings being 55

stitched along the top and side edges to the edges of the tip portions of the leather fronts of the fingers.

By the particular form of thumb back blank 5 10 having the main part 10' to match with the thumb front part 7 of the blank 1 and provided at one side thereof with the straight edge portions 11 and 12 diverging substantially away from each other and converging to a substantially projected intermediate portion, in conjunction with the blank 1 having the straight slit 8, as herein-before described, the seam between the edge portions 11 and 12 of the thumb back piece and the elongated edge portions along the slit 8 extends 15 forwardly of the crease or line of the inner side of the ball of the thumb. This construction provides for a snug fit of the glove to the hand in the crotch between the thumb and fore-finger, and the desired freedom in the movement of the 20 thumb and fore-finger in gripping objects, the particular location of the seam with reference to the crease or line of the inner side of the ball of the thumb also being advantageous in providing a durable construction.

25 The glove is shown provided with a tubular knit wrist portion 21 sewed thereto, and stitched to the wrist portion and to the wrist seam is a strip of leather 22.

The modified construction illustrated in Figures 9 to 13 of the drawings has a full cloth back 30 23. The construction comprises a main front blank 24 formed of a single piece of leather and having a palm portion 25, front thumb part 26, and finger sections 27, 28 which form the front 35 and sides of the first and fourth fingers. A piece of leather 29, shown in Figure 12, forms the fronts of the second and third fingers, said piece being folded along the slit 30 therein and the edge portions 31, 32 stitched to the edge portion 33 of the blank 24. The back of the thumb is formed 40 by a leather piece 34, this being of the same shape as the back thumb piece shown in Figure 5. The numerals 35 designate leather facings for the

back and sides of the tip portions of the fingers, these being similar in construction to and being stitched at their top and side edges to the edges of the tip portions of the leather fronts of the fingers, as in the construction illustrated in Figures 1 to 8.

In this modified construction, the glove is provided with the gauntlet 36, and the blank 24 has a lower portion 37 formed continuous therewith extending over and stitched to the gauntlet.

10 What I claim as new and desire to secure by Letters Patent of the United States is:

A glove comprising a continuous blank of leather constituting a palm section, front finger portions, and a front thumb portion projecting laterally from one side edge thereof, a cloth back for the glove, including a main back portion and finger backs, said first mentioned blank having a straight slit 8 extending a substantial distance at an inclination downwardly and inwardly from one side edge thereof below the base of the front of the first finger and creating corresponding elongated edge portions intermediate the said thumb and palm portions, and a separate thumb back portion of leather comprising a main part 25 of a shape to match with the front thumb portion and having at one side of said main part straight edge portions 11 and 12 to match with the said elongated edge portions along the slit 8 in the first mentioned blank, said straight edge 30 portions 11 and 12 diverging substantially away from each other and converging to a substantially projected intermediate portion, said main thumb back portion being stitched along its marginal edge to the edge of the front thumb portion, 35 the diverging straight edge portions 11 and 12 of the thumb back portion being stitched to the edge portions that extend along the slit 8, and the adjoining side edge portion of the thumb back portion being stitched to an edge portion of the back 40 of the glove.

EDWARD ELKUS.
